UNITED STATES PATENT OFFICE.

JOHN F. NEWSOM, OF PALO ALTO, CALIFORNIA.

DREDGING APPARATUS.

Application filed July 21, 1921. Serial No. 486,325.

To all whom it may concern:

Be it known that I, JOHN F. NEWSOM, a citizen of the United States, and a resident of Palo Alto, county of Santa Clara, State 5 of California, have invented a certain new and useful Dredging Apparatus, of which the following is a specification.

The invention relates to dredging apparatus and particularly to devices operating 10 from pontoons for effectively and economically recovering valuable mineral alluvial deposits from metalliferous ground.

This invention relates to an apparatus adapted for speedy, thorough and economic 15 extraction of alluvial deposits of metallic ore and other minerals from rough and irregular ground and which cannot be reached by the ordinary type of bucket or suction dredge and which are therefore lost.

20 The bucket-dredging and suction-cutting apparatus now in common use is too well known to require any detailed description, and consists of any known form of endless chain bucket-dredge or a cutter connected 25 with a gravel suction pump driven by an electric motor or other suitable source of power mounted upon a pontoon on which is also mounted a revolving screen and thwartship slices or launders in connection with 30 collecting and concentrating tables, the tailings being discharged over the stern of the pontoon upon ground already worked.

These bucket-dredges and suction-cutter dredges are from their nature adapted for 35 use only when the pontoon is afloat in a pond or paddock, whereas the dredge of my invention is adapted for use when the pontoon is floating on the pond or at rest upon the bottom of such pond or paddock after 40 the same has been pumped dry and after the bucket-dredge or suction-cutter dredge, as the case may be, has cleaned up the bottom as efficiently as the nature of their construction will allow.

45 My invention consists of a combination with any such known bucket-dredge or suction-cutter dredge, mounted on a pontoon, as generally above described of a rope tram and bucket elevating device comprising an 50 upwardly projecting derrick-pole or mast or other similar structure made of wood, steel or any other suitable material, from which are radially extended any number of wire ropes in any required direction and to any 55 required distance and anchored to posts, deadmen or other suitable anchors.

Supported upon each of these wires is a trolley or carrier of any desired form, preferably provided with a self-tripping arrangement and other automatic features as 60 in common use to which a bucket preferably provided with a self-dumping apparatus in common use, is suspended by means of a pull or hoisting line led down the derrick pole or mast and back to a winch mounted on the 65 superstructure of the pontoon and provided with any required number of drums.

Erected around the derrick pole or other structure before described is a hopper or receiver or receptacle erected in such manner 70 that the circumference, or outer edge of such receptacle, projects beyond the derrick mast or pole in every radial direction and is thus adapted to receive the material from the buckets operating from any radial position 75 and to discharge the same through a central outlet hole leading either directly, or by any suitable means, to a puddler or other disintegrating or washing device.

While in the drawings a funnel-shaped 80 hopper or receiver is shown, it will be understood that this receiver may be of any suitable form and arrangement and still be within the purview of this invention.

It is obvious now that with the wire ropes 85 disposed in any desired position and provided with dumping buckets, which will be filled by manual labor, and discharging at any point into the receiver or hopper, it will be possible to completely recover all mate- 90 rial left in the bottom of the pond or paddock, however rough or irregular the bedrock formation may be, by means of the rope tram and bucket elevating apparatus before described which is erected on a pon- 95 toon equipped with the ordinary endless chain bucket or suction cutter and accessory dredging apparatus now in common use.

The invention possesses other advan- 100 tageous features, some of which, with the foregoing, will be made manifest in the following description, where I shall outline in full that form of the invention which I have selected for illustration in the drawings accom- 105 panying and forming part of the present specification.

Referring to said drawings:

Figure 1 is a plan or top view of a dredge embodying my invention.

Figure 2 is a side elevation of the dredge. 110

Referring now in detail to the drawings the pontoon 1, which is water-tight, and con-

2
structed, with its superstructure of wood, steel or other suitable material, is adapted either to float in a pond or paddock or to rest stationary on the bottom of such pond or paddock after the water has been pumped out.

This pontoon 1 has erected upon it a suction cutter 2 of any known design (in the drawings the pontoon 1 is shown as fitted with a suction-cutter-dredge, but it can be equally well fitted with a bucket-dredge of any known design).

Connecting with the suction cutter 2 is a gravel pump 3, by means of which the material is forced through pipe 4 and led into the hopper or receiver 5 and is dropped by means of outlet hole 6 into the puddler or screen 7, whence it is discharged into thwartship sluices or launders 8 connecting with collecting or concentrating tables 9 from which the tailings are discharged in any convenient manner.

Mounted on the pontoon 1 is a derrick pole or mast 10, or other structure, from which are extended ropes 11 which may be anchored to posts or anchors 12.

Upon these wire ropes 11 are supported trolleys or carriers 13 of any desired form, preferably provided with self-tripping appliances and other automatic features commonly used. From the trolleys or carriers 13 are suspended buckets 14, preferably provided with self-dumping and other automatic features in common use, by means of a pull or hoisting line 15 which is led down the derrick pole or mast, or other structure 10, to a winch 16 provided with any required number of drums. Around the derrick-pole or mast or other structure 10, the hopper or receiver 5, described above, is erected in such manner that the circumference or outer edge of such receptacle projects beyond the derrick mast or pole in every radial direction, and that it thus enables the wire ropes 11 to be disposed in any radial position and to allow the buckets 14 to dump their contents into the hopper or receiver 5 at any point, and enables such contents to drop through the common outlet hole 6 into the puddler or screen 7, or enables the material so dumped to be disintegrated, while still in the hopper or receiver 5, by means of a jet of water under pressure being brought to bear thereon, thus eliminating the puddler or screen 7, and to be discharged through the common outlet hole 6 to the thwartship sluices or launders 8 and concentrating tables 9.

The rope tram and bucket elevating apparatus only comes into play after the suction-cutter or bucket-dredge has removed the ground above the top of the bedrock pinnacles while the pontoon is afloat, preparatory to cleaning out the earth from the holes and crevices in the bedrock by means

of the rope tram and bucket elevating apparatus above described.

While the buckets 14 are being loaded elevated and are dumping their contents into the hopper or receiver 5, suction cutter 2, 70 or any other pipe connected with a centrifugal pump mounted on the bows of the pontoon, will be lowered to the bedrock and the suction pump connected therewith placed in operation.

This will form a sump hole to which streams of water from various parts of the pit will be conducted, so that water will be provided for the receiving hopper 5 and for the concentrating tables 9, and at the same time raise to the receiving hopper 5 any portion of the ground which may be brought by the water current into the sump hole.

This will form a sump hole to which streams of water from various parts of the pit will be conducted, so that water will be provided for the receiving hopper 5 and for the concentrating tables 9, and at the same time raise to the receiving hopper 5 any portion of the ground which may be brought by the water current into the sump hole.

The whole general operation may be shortly described as follows:

The pond or paddock, on which it is desired to operate, is first flooded and the pontoon floated into it and placed in any required position, being moved about from time to time as occasion may require.

The suction cutter or bucket line, as the case may be, is then set in motion and proceeds to work all of the ground which it is possible to work by the present dredging practice.

After the suction cutters or bucket dredges have completed their work, the water in the pond or paddock is pumped out and the pontoon comes to rest in any convenient part of the paddock.

After the pontoon has so come to rest, the wire ropes are run out from the derrick pole or mast or other structure and anchored in any convenient positions, and the self-dumping buckets are set in motion.

The buckets are filled by manual labor and dump into the hopper above described, and so into the puddler or screen and thence to the concentrating tables, or direct to the concentrating tables after disintegration in the hopper or receiver, as above described.

The outstanding feature of my invention is that it enables the ground to be worked, so far as possible, by the ordinary dredging process, and enables the remaining ground left in the inequalities by that process to be subsequently completely worked, the whole being accomplished by one combined unit machine mounted on one pontoon and in one practically continuous operation.

It is to be understood that various modifications may be made in the construction and arrangement as shown in the drawings, and as particularly hereinbefore described, and still be within the scope of this invention.

I claim:

1. The combination with a pontoon having suction type or bucket type dredging ap-

- paratus arranged thereon, of an elevated structure on said pontoon, a cable extending from said structure to a point remote from the pontoon, a bucket arranged to be moved 5 along said cable to convey material and discharge it into a receptacle on said pontoon and sluices into which the material elevated by the bucket or the dredging apparatus is directed.
- 10 2. The combination with a pontoon having suction type or bucket type dredging apparatus arranged thereon, of a hopper into which said dredging apparatus discharges, an elevated structure on said pontoon adjacent 15 said hopper, a cable secured to said structure and extending to a point remote from said pontoon and a movable bucket on said cable arranged to discharge its contents into said hopper.
- 15 3. The combination with a pontoon having dredging apparatus arranged thereon, of a hopper on said pontoon, an elevated structure arranged adjacent said hopper, a cable secured to said structure and extending across 20 said hopper to a point remote from said pontoon and a bucket movable along said cable adapted to discharge into said hopper.
- 25 4. The combination with a pontoon, of a hopper arranged thereon, an elevated structure arranged adjacent said hopper, a cable secured to said structure and extending across said hopper to a point remote from said pontoon, a bucket movable along said 30 cable

cable and adapted to discharge its contents into said hopper and a pump having a discharge pipe opening into said hopper. 35

5. The combination with a pontoon, of a receiver arranged thereon, an elevated structure arranged adjacent said receiver, a cable secured to said structure and extending to a point remote from said pontoon, a bucket movable along said cable adapted to convey material which is directed into said receiver and a pump having a discharge pipe for directing water into said receiver. 40

6. The combination with a pontoon, of a receiver arranged thereon, a cable disposed adjacent said receiver and having one end anchored at a point remote from the pontoon, a bucket movable along said cable and 45 adapted to convey material to said receiver and a pump for supplying the water necessary to wash said material. 50

7. The combination with a pontoon, of a hopper arranged thereon, an elevated structure arranged adjacent said hopper, a cable secured to said structure and extending across said hopper to a point remote from said pontoon, a bucket movable along said cable adapted to discharge material into said 55 hopper, sluices arranged below said hopper and a pump for supplying the water necessary to wash the material. 60

In testimony whereof, I have hereunto set my hand.

JOHN F. NEWSOM.
